(57) **CLAIM**

The ornamental design for a trimplate for an automobile headrest video system, as shown and described.

DESCRIPTION

FIG. 1 is a front perspective view of a trimplate for an automobile headrest video system showing my new design.

FIG. 2 is a front plan view of thereof.

FIG. 3 is a top plan view of thereof; and,

FIG. 4 is a front perspective view of thereof with the monitor pivoted outwardly.

In the drawings, the broken lines show portions of an automobile headrest and video system and form no part of the claimed design.
